Specification for Design.

Patented May 25, 1920.

Application filed November 21, 1919. Serial No. 339,736. Term of patent 7 years.

To all whom it may concern:

Be it known that I, HARRISON L. BERG, a citizen of the United States, residing at Everett, in the county of Middlesex and State of Massachusetts, have invented a certain new, original, and ornamental Design for a Fender for Automobiles, of which the following is a specification, reference being had to the accompanying drawing, forming part thereof.

In the drawings:

Figure 1 is a front elevation of a fender, showing my new design.

Fig. 2 is a bottom plan of the same.

Fig. 3 is a sectional elevation taken on line 3—3 of Fig. 1.

I claim—

The ornamental design for a fender for automobiles, as shown.

In testimony whereof I have hereunto set my hand in presence of two subscribing witnesses.

HARRISON L. BERG.
